UNITED STATES PATENT OFFICE.

ERLE R. SHEPPARD, OF NEW YORK, N. Y.

DESIGN FOR A CARD-CASE OR SIMILAR ARTICLE.

40,859.

Specification for Design.

Patented Sept. 6, 1910.

Application filed July 7, 1910. Serial No. 570,910. Term of patent 7 years.

To all whom it may concern:

Be it known that I, ERLE R. SHEPPARD, a citizen of the United States, residing at New York, in the county of New York and State of New York, have invented a new, original, and ornamental Design for a Card-Case or Similar Article, of which the following is a specification.

The accompanying drawing is a view in elevation of a card case or similar article having my design applied thereto.

What I claim is:—

The ornamental design for a card case or similar article, as shown.

ERLE R. SHEPPARD.
